ELECTRIC DISCHARGE LAMP

Robert F. Reed, Danvers, Mass., assignor to Hy-grade Sylvania Corporation, Salem, Mass., a corporation of Massachusetts

Application February 15, 1939, Serial No. 256,498

6 Claims. (Cl. 176—126)

This invention relates to electric discharge devices, and particularly to such devices employing a thermionic electrode.

An object of the invention is to provide for such a device an electrode whose lead-in and support wires are arranged to start an auxiliary discharge sufficient to facilitate the starting of the main discharge in the device.

Another object is to properly proportion the various parts of the electrode and discharge device and their auxiliary equipment to insure that such auxiliary discharge occurs.

Still another object is to provide an electrode mount which is easily assembled in manufacture.

Other objects and advantages of the invention will be apparent from a study of the following specification, taken in conjunction with the accompanying drawing, in which:

Figure 1 is a profile view, partly in section, of a lamp according to the invention;

Figure 2 is a view of the electrode of Figure 1, in a plane perpendicular to that of Figure 1;

Figure 3 is a view of the clamped end of the filament of that electrode;

Figure 4 is a view of the electrode arranged in a slightly different manner; and

Figure 5 is a view of the electrode of Fig. 4, in a plane perpendicular to that of Fig. 4.

In Figure 1, the tubular glass envelope 1 is sealed at each end to a reentrant stem 2 through which the lead-in wires 3, 4 pass at the press 13, to support the coiled wire electrode 5. The envelope has the coating 6 of fluorescent material on its inner surface, and has a filling of inert gas and mercury vapor, for example. The exhaust tube 7, which may be present on one or both of the stems 2, seals the tube. The lead-in wires project forward a short distance from the stem, and are bent at point 8 into a plane perpendicular to the tube axis.

Figure 2 shows a plan view of the electrode in that perpendicular plane the lead-in wires 3, 4, project toward each other in opposite but essentially parallel directions to the points 9, 10, where they are bent to meet the ends 11, 12 of the filament 5, which is preferably a doubly-coiled filament as shown. The ends 11, 12 are thus singly coiled, and are clamped to the lead-in wires as shown in Figure 3, in which the end 9 of the lead-in wire is bent back and against the filament end 11, to hold it securely. Such clamping is a much better means of holding the filament than is the welding often employed. The coiled coil filament is preferably coated

with an electron-emitting material, such as one or more of the oxides of the alkaline earths.

If desired, the electrode may be arranged as in Figs. 4 and 5, in which part of each lead-in or support wire 3, 4 extends along and parallel to the filament coil 5.

In operation, the lead-in wires 3, 4 are connected to a source of voltage sufficient to bring the filament to an electron-emitting temperature. The filament is preferably proportioned so that the voltage drop across it with a current sufficient to bring it to the electron-emitting temperature is slightly greater than the resonance or ionization voltage of the gas or vapor

15 in the tube. There will then be sufficient voltage between each end of the filament and the lead-in wire to the opposite end to cause a discharge through the gas between said end, say end 11, and lead-in wire, say 4. This local discharge will excite the gas along the main path along the length of the glass envelope and permit the starting of that discharge. The filament voltage is 20 preferably applied a few seconds before the main voltage, and may be cut off as soon as the main voltage is applied the filament then acting as a self-heating electrode.

I prefer that the filament in my mount be supported in what I will call a "left-handed" direction. On looking down at the filament, as in 25 Figure 2, we find that the filament is placed along a diagonal extending downward to the left (or upward to the right, which is the same thing). I find that such an arrangement is to be preferred, for manufacturing purposes, to the arrangement in which the filament extends along the opposite, or right handed diagonal (which, of course, extends downward to the right).

The filament 5 is preferably made of tungsten wire, and by properly proportioning the diameter and length of the wire, the filament can be made to have a voltage drop greater than the resonance or ionization voltage of the gas or vapor in the tube at a current sufficient to raise the temperature of the filament to an electron-emitting value 40 sufficient to operate the discharge.

What I claim is:

1. In an electric gaseous discharge device, a tubular glass envelope, a stem sealed to an end of said envelope to close off the same, two lead-in wires sealed through said stem in a direction 45 approximately parallel to the axis of the tubular envelope and bent in opposite but parallel directions into a plane perpendicular to said axis and at a short distance above the press of the stem, a doubly coiled, oxide-coated filament each of

whose ends is clamped to an end of one of said lead-in wires for support and electrical connection, the filament being in substantially the same plane with the bent portions of the lead-in wires, the length of the filament being such that each of its ends is disposed near the lead-in wire to the opposite end.

2. In an electric gaseous discharge device, a glass envelope, a stem sealed to an end of said envelope to close off the same, two lead-in wires sealed through the press of said stem and bent into a plane substantially perpendicular to the axis of said stem, an oxide-coated coiled filament in said plane, each end of said filament being clamped to an end of one of the lead-in wires, the lead-in wires being disposed so that each end of the filament is near a portion of the lead-in wire to the other end of the filament.

3. The combination of claim 2, a filling of ionizable gas within the envelope, and in which the filament is proportioned to have a voltage drop greater than the ionizing voltage of said gas for a current sufficient to raise the filament to an electron emitting temperature.

4. The combination of claim 2, a filling of 25 ionizable gas within the envelope, and in which the filament is proportioned to have a voltage

drop greater than the ionizing voltage of said gas for a current sufficient to raise the filament to an electron emitting temperature, and in which the filament is arranged in a left-handed direction.

5. In an electric gaseous discharge device, a tubular glass envelope, a stem sealed to an end of said envelope to close off the same, a doubly-coiled, oxide-coated tungsten wire filament supported with its axis straight and substantially in a plane perpendicular to the axis of said tubular envelope, and two wires extending parallel to said filament and on opposite sides of said filament and in substantially the same perpendicular plane as the filament, each of said straight wires being connected to an end of said filament.

6. The combination of claim 5, a filling of ionizable gas within said envelope, and in which the filament is proportioned to have a voltage drop greater than the ionization voltage of the gas for a current sufficient to raise the filament to an electron emitting temperature, in order that a local discharge may pass from said filament to said wires.

ROBERT F. REED.
